UNITED STATES PATENT OFFICE.

ERIC P. ALTBURG, OF COLUMBIANA, OHIO.

DESIGN FOR A TIRE

57,070.

Specification for Design.

Patented Feb. 8, 1921.

Application filed May 18, 1920. Serial No. 382,413. Term of patent 14 years.

To all whom it may concern:

Be it known that I, ERIC P. ALTBURG, a citizen of the United States, residing at Columbiana, in the county of Columbiana and State of Ohio, have invented a new, original, and ornamental Design for a Tire, of which the following is a specification, reference being had to the accompanying drawing, forming part thereof.

The figure is a perspective view of a tire, showing my new design.

I claim:

The ornamental design for a tire as shown.

ERIC P. ALTBURG.
